BILLFOLD

Harold B. Potter, Coshocton, Ohio

Application May 18, 1949, Serial No. 2,727

Term of patent 7 years

(Cl. D87—3)

To all whom it may concern:

Be it known that I, Harold B. Potter, a citizen of the United States, residing at Coshocton, in the county of Coshocton and State of Ohio, have invented a new, original, and ornamental Design for Billfold, of which the following is a specification, reference being had to the accompanying drawing, forming part thereof.

Fig. 1 is a front perspective view of a billfold embodying my new design, the back thereof being plain; and

Fig. 2 is a front perspective view of the billfold in open position.

I claim:

The ornamental design for a billfold, as shown.
HAROLD B. POTTER.
